[57] CLAIM

The ornamental design for the combined cigarette snuffer and holder, substantially as shown and described.

DESCRIPTION

FIG. 1 is a top perspective view of my combined cigarette snuffer and holder, showing my new design;
FIG. 2 is a bottom perspective view thereof;
FIG. 3 is a top plan view thereof;
FIG. 4 is a bottom plan view thereof.
FIG. 5 is a side elevational view, the opposite side being a substantial mirror image thereof.
